SYLVESTER W. CROWLEY, OF WEEHAWKEN, NEW JERSEY, ASSIGNOR TO DE FOREST
RADIO TELEPHONE & TELEGRAPH CO., OF JERSEY CITY, NEW JERSEY, A CORPORA-
TION OF DELAWARE.

ELECTRON-DISCHARGE DEVICE.

Application filed February 2, 1924. Serial No. 690,191.

This invention relates to electron discharge devices and more particularly to the plate and its mounting used in connection with such devices.

5 The objects of the invention are to provide a plate of improved structure; to enable the plate to be readily mounted in place; to obtain the proper formation of the plate prior to inserting the same in the electron 10 discharge device; to obtain a plate which will be rigid; to secure a supporting means which will properly carry the plate; to secure simplicity of construction and operation, and to obtain other advantages and 15 results as may be brought out in the following description.

Referring to the accompanying drawing in which like numerals of reference indicate similar parts throughout the several views; 20 Figure 1 is a side elevation of an electron discharge device embodying my invention, and showing the bulb broken away for showing the parts within;

Figure 2 is a plan of the invention mounted upon the stem;

Figure 3 is a vertical sectional view as upon line 3—3 of Figure 2;

Figures 4, 5 and 6 are perspective views of the plate showing the same in successive 30 stages of manufacture;

Figure 7 is a view similar to Figure 1 showing a modified arrangement of parts;

Figure 8 is a vertical sectional view of Figure 7 corresponding to Figure 3;

35 Figure 9 is a perspective view of plate and grid positioned therein; and

Figure 10 is a side elevation of the grid.

In the specific embodiment of the invention illustrated in said drawing, reference 40 numeral 1 indicates the usual base and numeral 2 indicates the usual bulb carried by the base within which is mounted a stem 3 carrying the operative parts of the electron discharge device. It is usual to provide several leads and supports for the operative

45 parts of the electron discharge device, extending the same upwardly through the end of the stem wherein they are sealed as shown in Figure 3. In carrying out my invention, 50 I provide a lead 4 and another wire 5 both of which constitute supports projecting in parallel relation to each other from the top of the stem 3. In manufacture of devices of this sort, I have found it practical to very

55 accurately position the supports 4 and 5 so their distance apart will be substantially the same in every case.

The supports 4 and 5 are adapted for mounting a plate 6, the structure of which forms an essential part of the present invention. Said plate is preferably stamped out 60 of a sheet of metal of proper thickness and material so as to provide extensions 7 and 8 at the central part of opposite longitudinal edges. The plate is then bent into substantially cylindrical shape so that said longitudinal edges will be parallel and adjacent to each other and the said extensions will be flatwise of each other and project from the cylindrically shaped plate.

70 One of the extensions, as 7, has a tongue 9 at its end away from the body portion of the plate, and the other extension, as 8, is provided with laterally extending tabs 10 adjacent its outer end but extending from the side edges of said extension. After the extensions are brought flatwise together, the longitudinally extending tongue 9 on an extension 7 is bent over the upper edge of the other extension 8 so as to hold the two together as clearly illustrated in Figure 5.

75 Tabs 10 are bent into a perpendicular position with respect to the said extension both in the same general and parallel direction. After this operation upon the various parts, the outwardly extending tabs 10, 10 are

80 curled inwardly so as to form substantially parallel sockets extending in a direction transverse to the axis of the cylindrical portion of the plate and in the same general 85 direction as the said extensions. These parallel sockets formed by the curling in of the said tabs are spaced the same distance apart as the spacing of supports 4 and 5 on the stem. Accordingly, in assembling the plate

90 upon the stem, the curled tabs or sockets may be slid downwardly onto said supports without the necessity of any further adjustment or manipulation.

95 Preferably the extensions 7 and 8 are bent so as to substantially engage the body portion of the plate as clearly shown in Figure 3. This enables the supports to be inserted from the end of the socket which is nearest the inner end of the extension and accordingly obtains a more solid support for the plate because of the attachment closely

100 adjacent to the stem. Furthermore, this 105

manner of mounting has the effect of an underslung support which obtains the greatest amount of compactness and rigidity which is possible in this type of plate.

5 The same construction of plate as above described may be employed in an electron discharge device without bending the extensions back toward the plate. In other words, the extensions may be left projecting

10 outwardly from the plate so that when the plate is mounted it will be substantially above the stem. By way of illustration, I have shown this structure in Figures 7 to 10 wherein the base 1, bulb 2 and stem 3 re-

15 main the same, as well as the supports 4 and 5 for the plate. The plate itself, except for the bending of the extensions, also remains substantially as before. However, for purposes of definiteness I have indicated the

20 plate with reference numeral 11 provided with extensions 12 and 13, one of which, as 12 is provided with a tongue 14 at its end which is bent over the other extension 13 for securing the two together. Extension 13

25 is provided with curled tabs 15 similar to tabs 10 already described. As will be noted from the several figures now being described the extensions project outwardly from the plate in a diametric direction and the plate

30 is mounted above the stem, the said curled tabs or sockets 15 sliding downwardly on the supports 4 and 5.

Within the plate is provided a grid 16 preferably in the shape of a coil and carried

35 by a U-shaped bracket 17 which preferably extends through the said coil and is welded to each convolution of the grid. Said bracket 17 provides downwardly extending ends 18, 18 which are subsequently welded

40 to supports 19, 19 projecting upwardly from the stem. It is to be noted that the diameter of the grid and the distance which the ends 18 of the bracket 17 extend is so proportioned that the grid with its attached

45 bracket may be inserted into the plate after

the plate has been assembled. The fact that the extensions on the plate are held together at the outer ends enables the plate to be spread so as to provide a gap between the inner ends of the said extensions through which the projecting end 18 of the bracket may pass when the grid is slid into place. After the parts are assembled and the plate slid onto its supports, the bracket ends 18 may be welded to their supports and the 50 sockets 15 welded to their supports. By use of suitable apparatus these welding operations may all be done at once by a spot welding machine thus enabling the device to be made with considerable rapidity.

There are a number of details in the showing herein, such as the exact size and shape of the plate, the length of the extensions, the direction of bending of the tabs, which may be modified as found desirable 55 and still obtain the benefits of my invention. Furthermore, there may be other modifications and changes which may be incorporated in the manufacture and use of my invention, and I do not wish to be understood as limiting myself to the exact structure shown except as set forth in the following claim when construed in the light of the prior art.

Having thus described my invention, I 75 claim:—

In an electron discharge device construction including an evacuated vessel having a stem, a cylindrical plate having two juxtaposed tabs secured together, a plurality of sockets formed on one of said tabs lying centrally with respect to the height of the plate and transversely of the plate and supports projecting from said stem a distance substantially equal to the diameter of 80 the plate, said supports receiving said sockets to support the plate transversely with respect to the stem and in close proximity thereto.

SYLVESTER W. CROWLEY.
